WILLIAM F. HENDRY, OF OSSINING, AND CHARLES J. NELSON, OF NEW YORK, N. Y.,
ASSIGNORS, BY MESNE ASSIGNMENTS, TO NATIONAL CARBON COMPANY, INC., OF
NEW YORK, N. Y., A CORPORATION OF NEW YORK.

FLASH LIGHT.

Application filed August 1, 1925. Serial No. 47,583.

This invention relates to flashlights, and more particularly to switches for electrical hand lamps.

It is the object of the present invention 5 to provide an improved flashlight switch of the three-position type, that is to say, in which the switch may be held in three distinct positions; in one, the lamp cannot be lighted; in another, the lamp may be 10 flashed; and in the third, the lamp is permanently lighted.

With this object in view we provide a switch composed of relatively few parts which may be readily mounted on a casing 15 and yet so firmly held that its accidental dislocation is effectively prevented.

The nature of the invention will more clearly appear from the following description of a preferred embodiment thereof and 20 the appended claims.

In the drawings, Fig. 1 is a vertical cross-section of a flashlight; and Fig. 2 is a section of the switch along lines 2—2 of Fig. 1.

The flashlight consists of a tubular metallic casing 1 enclosing a dry cell battery 2. The zinc electrode of the battery is in contact with a flange 3 projecting from a cap 4 which is in screw-threaded engagement with the lower end of the tubular casing 1. 25 The carbon electrode 5 of the battery contacts with one terminal 6 of an incandescent electric light bulb 7. The other terminal of the lamp 7 is connected with a metallic screw-threaded base 8. The base 8 is in screw-threaded engagement with a metallic socket 9 provided with a cup-shaped flange 10. The cup-shaped flange 10 is stamped out of a resilient piece of metal with a plurality of spring fingers like 11. These fingers are 30 bent up at right angles. The socket 9 and its flange 10 are fastened to a disc 15 of insulating material which is seated on an annular shoulder 16 provided in the casing 11. On top of the lamp and socket assembly 35 is placed a metallic reflector 17 provided with an opening 18 which is sufficiently large to permit passage of the light bulb 7. The reflector is seated on the spring fingers 11 and is firmly held in place by means of a lens 19 clamped to the end of the casing 1 by means of a ring 20. The reflector 17 is insulated from the casing by means of a sleeve 21 seated on a shoulder 22 provided in the bell-shaped end 23 of

casing 1. By rotating the cap 4 the battery 55 2 may be reciprocated within the casing and will force the bulb 7 with its socket against the tension of spring fingers 11, effecting thus any desired focusing. The spring fingers slide along the lower surface 60 of the reflector 17 and when the cap 4 is unscrewed, cause the bulb with its socket and the battery 2 to return to their normal position. At all times the spring fingers maintain the bulb 7 properly centered with 65 respect to opening 18.

The socket 9 is prevented from rotating by means of a conductor or contact spring 24 passing through a notch 25 provided in the insulating disc 15. The circuit of the 70 lamp extends through terminal 6, the battery 2, the casing 1, contact spring 24, reflector 17 with which the spring is in engagement, the spring fingers 11, the flange 10, socket 9, base 8, back to the other terminal 75 of the lamp.

The spring 24 forms part of a pile-up mounted on the casing 1 by means of rivets 27. The pile-up is composed of the spring 24, an insulating wrapper 28 surrounding 80 a section of the spring, a sheet of insulation 29, a relatively light spring 30 and a heavy spring 31. The holes in spring 24 through which rivets 27 pass are relatively large so that the spring remains insulated from the 85 casing. The springs 30 and 31 are electrically connected with the casing 1 through rivets 27. The lower end 32 of spring 24 projects beyond the insulating wrapper 28 and is bent down to rest upon the sheet of 90 insulation 29. The free end 33 of the spring 30 is bent up and bears against the upper edge of a slide 34, pressing said slide against the inside of the casing 1. The slide has depending flanges 35 to hold the dry cells 95 out of contact with the spring pile-up. The lower part of the heavy spring 31 is bent into an elbow 36 normally lying in a corrugation 37 provided in the slide 34. The free end of the spring 31 is formed into a 100 finger 38 serving as a stop for the slide by engaging the bent-down end 43 of the corrugated part thereof. A button 39 projecting from the slide through an opening 40 in the casing 1 may be engaged to move 105 the slide up and down. The slide with its corrugated part, button 39 and flanges 35 is preferably formed of one piece of metal.

With the slide in the position illustrated in the drawing the circuit of the lamp 7 is interrupted at contact 32. The button 39 may now be depressed against the tension 5 of springs 30 and 31 without, however, closing the circuit. The two springs serve to restore the slide to its normal position and, owing to its engagement by the spring near the upper and lower ends, the slide remains 10 properly seated. The end 38 of spring 31 prevents the slide from slipping within the casing 1 when depressed. This is particularly important in case the switch is handled with the casing empty. When it is 15 desired to flash the light, the slide 34 is moved upward by means of button 39 until the elbow 36 comes to rest in the corrugation 41. When the button 39 is now depressed, the upper end of the slide 34 will 20 engage the spring end 32, which lies in a lower plane than the slide, and completes the lamp circuit. When it is desired permanently to light the lamp, the slide is moved into its upper end position until the elbow 25 36 comes to rest in the corrugation 42, in which position the upper end of the slide will be wedged between the casing 1 and an intermediate portion of the spring 24, which lies substantially in the plane of the slide, 30 permanently closing the lamp circuit.

What we claim is:

1. In a flashlight, a casing, a battery and a bulb enclosed therein, a slide and a co-operating contact for controlling the bulb circuit, and two springs mounted on the casing on one side of said slide, the free ends of said springs pressing the two edges of said slide against said casing.
2. In a flashlight, a casing, a battery and a bulb enclosed therein, a slide and a co-operating contact for controlling the bulb circuit, and two springs mounted on the casing in a pile-up with said contact, the free ends of said springs bearing against 40 two edges of said slide.
3. In a flashlight, a casing, a battery and a bulb enclosed therein, a slide and a co-operating contact for controlling the bulb circuit, and two springs mounted on the casing in a pile-up with said contact, the free ends of said springs bearing, respectively, against the upper and lower 50 ends of said slide.
4. In a flashlight, a metallic casing, a battery and a bulb enclosed therein, a metallic slide and a co-operating contact for controlling the bulb circuit, insulation separating said contact from said casing, and two springs mounted on the casing in a pile-up 55 with said contact, the free ends of said springs bearing, respectively, against the upper and lower ends of said slide pressing it against the inner surface of said casing.
5. In a flashlight, a casing, a battery and a bulb enclosed therein, a slide and a co-

operating contact for controlling the bulb circuit, a corrugated surface and a projection on said slide, and two projections in the free end of said contact, one cooperating with said corrugated surface and the other 70 engaging the said slide to limit its movement.

6. In a flashlight, a casing, a battery and a bulb enclosed therein, a three-position switch comprising a slide and a cooperating 75 contact for controlling the bulb circuit, two springs mounted on the casing in a pile-up with said contact, the free ends of said springs bearing respectively, against the upper and lower ends of said slide, and a button projecting from said slide to the outside of said casing by means of which the slide may be moved with respect to said contact against the tension of said springs.

7. In a flashlight, a casing, a battery and a bulb enclosed therein, a contact connected with said bulb, a slide cooperating with said contact for controlling the bulb circuit, said contact and slide being normally out of reach from each other, two springs mounted on 80 the casing in a pile-up with said contact, the free ends of said springs bearing, respectively, against the upper and lower ends of said slide, and a button projecting from said slide to the outside of said casing by means of which the slide may be moved 85 against the tension of said springs longitudinally within the reach of said contact and depressed into engagement therewith.

8. In a flashlight, a metallic casing, a battery and a bulb in said casing, a metallic slide within said casing, said slide having a corrugated surface near one end, a pile-up 100 mounted on said casing above said slide, said pile-up comprising an insulated contact 105 spring having one end in contact with the bulb circuit and the other end terminating above said slide, a spring the free end of which presses one edge of said slide against the casing, and a spring having a projection in its free end cooperating with said corrugated surface.

9. In a flashlight, a metallic casing, a battery and a bulb in said casing, a metallic slide within said casing, said slide having a corrugated surface near its lower end, a pile-up mounted on said casing above said slide, said pile-up comprising an insulated contact spring having one end in contact 115 with the bulb circuit and the other end terminating above the upper end of said slide and below the plane thereof, a spring the free end of which presses the upper edge of said slide against the casing, a sheet of insulation projecting between the lower 120 ends of said contact spring and spring, and a spring having projections in its free end 125 cooperating with the corrugated lower end of said slide.

10. In a flashlight, a metallic casing, a 130

battery and a bulb in said casing, a three-position switch comprising a metallic slide within said casing, said slide having a corrugated surface and a turned-down part 5 near its lower end, a pile-up mounted on said casing above said slide, said pile-up comprising an insulated contact spring having one end in contact with the bulb circuit and the other end terminating above the 10 upper end of said slide and below the plane thereof, an intermediate portion of said spring lying substantially in the plane of said slide, a spring electrically connected with the casing and having a free end which presses the upper edge of said slide against 15 the casing, a sheet of insulation projecting between the lower ends of said contact spring and spring, and a spring having an elbow in its free end cooperating with the corrugated lower end of said slide, the free 20 end of said last mentioned spring being formed into a finger serving as a stop for said turned-down part.

In testimony whereof we have signed our names to this specification this 13th day of 25 July 1925.

WILLIAM F. HENDRY.
CHARLES J. NELSON.
